UNITED STATES PATENT OFFICE.

JOHN ROBERT WATTS, OF SHEFFIELD, ENGLAND.

TROUSERS PRESS.

Application filed February 3, 1922. Serial No. 533,935.

To all whom it may concern:

Be it known that I, JOHN ROBERT WATTS, a subject of the King of England, residing at Sheffield, in Yorkshire, England, have invented certain new and useful Improvements in or Relating to Trouser Presses; and I do hereby declare that the following is a full, clear, and exact description of the same.

10 This invention relates to trouser presses of the kind in which pressure is applied between upper and lower hinged boards by the aid of arms pivoted near the edges of the lower board, usually at the ends of transverse ribs or metal strips, and engaging like transverse ribs on the upper board, the object of the invention being to provide improvements in the construction with a view to simplify manipulation.

20 The pressure has usually been applied by nuts on screw-threaded ends of the arms, although various forms of cam levers for applying pressure have been used, and it has been proposed to pivot cam-levers to 25 nuts on such pivoted arms where the boards are not hinged together. According to the present invention, however, the upper and lower boards are hinged together on one side, preferably by direct pivotal engagement of transverse ribs on the two boards, and a member (which is hereinafter referred to as a "planetary member" to denote that it is rotatable about its own axis, which axis may be revolved about an axis on the lower 35 board) is journalled in an arm which is pivoted to the other side of the bottom board. Co-operating surfaces are provided on the planetary member and on the upper board (preferably on a rib thereof) which 40 surfaces are so shaped that pressure is applied between the boards when the surfaces are brought into contact with one another and the planetary member is turned about its axis. When the pressure between the 45 upper and lower boards may be more or less concentrated, as in clamping one end of a pair of trousers before stretching the garment, a single set of co-operating surfaces may be provided on the planetary member 50 and on the upper board. When, however, it is desired to distribute the pressure, as in pressing a pair of trousers, instead of providing a number of independently operated pressure devices, it is preferred to 55 journal a single planetary member between two arms spaced apart on the lower board

and to provide two or more sets of co-operating surfaces on the member and on the upper board respectively spaced apart to distribute the pressure so that a single 60 operation of one handle with which the planetary member is furnished is sufficient to apply pressure over the desired extent.

The co-operating surfaces on the planetary member and on the upper board preferably comprise an eccentric disc or cam on the planetary member capable of engaging a rib on the upper board and of applying pressure thereto. A retaining catch for the disc may be provided on the upper board 65 and is preferably furnished by making the surface on the upper board which cooperates with the eccentric disc concave in shape. The disc may also be shaped to provide a stop contacting with the rib of 70 the upper board to limit the movement of the planetary member. By forming the disc with a tangential flat portion at the desired place, or with a part shaped to correspond with the co-operating surface on 75 the upper board, not only will such a stop be furnished thereby, but the planetary member may be retained in the pressure producing position when the tangential flat portion or corresponding surface on the disc 80 is brought into contact with the co-operating surface on the upper board.

In the accompanying drawings:—

Figure 1 is a plan of a trouser press according to the present invention. 90

Figure 2 is a sectional end view of Figure 1 on the line 2—2 thereof, showing the means for applying pressure turned clear of the edge of the press.

Figure 3 is an end view of part of the 95 press showing the means for applying pressure moved partially towards the operative position.

Figure 4 is a view similar to Figure 3 showing the parts in position applying 100 pressure.

Figure 5 is a view similar to Figure 4 illustrating a modification.

Figure 6 is an enlargement of part of Figure 5. 105

Figure 7 is an end view illustrating a further modification and Figure 8 is a sectional end view taken on the line 8—8 of Figure 1.

Like reference numerals indicate like parts throughout the drawings. 110

The upper board 1 is of the usual construction comprising two longitudinal boards

connected together by a pair of transverse ribs 2. It is hinged at one side to the bottom board 3 preferably by direct pivotal engagement of the ribs 2 with similar transverse ribs 4 secured to the underside of the lower board 3, for which purpose the ribs 2 are formed with projecting tongues 5 on one side of the press having lateral extensions engaged by forked upturned portions 6 of the lower board ribs 4.

A planetary member 7 is journalled between arms 8 which are pivoted at or near the edge of the lower board 3 on the side opposite to the hinges 5, 6. In the construction illustrated in Figures 1, 2, 3, and 4, the two arms 8 are provided by suitably bending the ends of a rod rotatably mounted in the ends of the ribs 4 parallel with the edge of the lower board 3. The ends 20 of the planetary member 7 and of the arms 8 are formed with corresponding pivots and bearings which are caused to engage one another when bending the arms 8 into position. If desired, however, other means for pivoting the planetary member 7 between the arms 8 may be provided.

The arms 8 are spaced apart on the bottom board 3, with the two pairs of ribs 2, 4, between them. The length of the planetary member 7 is governed by the distance apart of the arms 8 and it is provided with a handle 9 by means of which it may be turned about either its own axis or that of the arms 8; it is also furnished with suitably shaped surfaces capable of thereby being brought into contact with the ribs 2 and of co-operating therewith to apply pressure between the upper and lower boards. As illustrated in Figures 1 to 4 the planetary member 7 is provided with an eccentric disc or cam 10 opposite each of the ribs 2. In operation the arms 8 are turned clear of the edge of the press as shown in Figure 2, the upper board 1 is raised about its hinges 5, 6, the garment to be pressed is placed in position the upper boards are turned down thereon and the arms 8 are raised to a vertical position as shown in Figure 3, the eccentricity of the discs 10 enabling them to clear the ends of the ribs 2 as shown in Figure 3. Pressure may now be applied between the upper and lower boards by turning the planetary member about its own axis to bring the eccentricities 10 into the position shown in Figure 4. In order to limit rotation of the planetary member 7 when the maximum pressure has been applied, one or both of the eccentric discs 10 may be provided with a tangential portion 11 adapted

to come into contact with the surface of the 60 ribs 2 as shown in Figure 4.

A retaining catch may be provided to hold the parts in the position shown in Figures 5 and 6. It is conveniently furnished by curving that part of the surface of the ribs 65 2 which cooperates with the edge of its eccentric 10 to apply pressure between the boards as shown at 12 in Figures 5 and 6. The curved concave surface 12 may either be provided by suitably bending the ribs 2 70 or otherwise as desired. When the curved surface 12 is employed it is preferred to modify the tangential flat portion 11 to correspond in shape therewith as indicated in Figure 6.

As a modification the eccentric discs 10 may be replaced by simple arms or the like 13 on the planetary member 7 co-operating with suitably shaped surfaces 14 on the ribs 2 as illustrated in Figure 7.

It will be appreciated that by spacing apart the arms 8 and the discs 10 or arms 13 pressure applied may be distributed along the whole length of the upper board 1 by a single operation of the handle 9. Where, however, the pressure may be concentrated the planetary member 7 may be provided with a single disc as shown at the left-hand end of Figure 1 and in Figure 8, where means are illustrated for clamping the ends 90 of a pair of trousers before stretching them, comprising a single rib 15 connecting two clamping boards 16 and hinged to a like rib 17 secured below the lower board, the rib 17 carrying the arms 18 between which the 95 planetary member 19 with its handle 20 is pivoted.

What I claim is:—

In a trousers press, the combination of upper and lower boards hinged together at 100 one side, two arms spaced apart and pivoted at the other side of the lower board, a planetary member journalled between the said arms, a handle extending radially from the said planetary member, ribs on the upper board spaced apart, eccentric discs on the planetary member each having a flattened portion parallel to the said handle, the rounded portion of each disc adapted to engage the upper surface of a rib and the flattened portion of each disc being capable of coming into contact with a rib to limit the rotational movement of the planetary member in one direction.

In testimony whereof I hereunto affix my 115 signature.

JOHN ROBERT WATTS.
